UNITED STATES PATENT OFFICE

106,975

DESIGN FOR A COMBINATION PENCIL STAND AND ASHTRAY

Hugo Heizmann, Boston, Mass.

Application September 21, 1937, Serial No. 71,711

Term of patent 14 years

To all whom it may concern:

Be it known that I, Hugo Heizmann, a citizen of the United States, residing at Boston, in the county of Suffolk and State of Massachusetts, have invented a new, original, and ornamental Design for a Combination Pencil Stand and Ashtray, of which the following is a specification, reference being had to the accompanying drawing, forming part thereof.

I claim:

The ornamental design for a combination pencil stand and ashtray as shown.

HUGO HEIZMANN.
